UNITED STATES PATENT OFFICE.

CHARLES J. MILLER, OF MINNEAPOLIS, MINNESOTA.

STORE-SERVICE APPARATUS.

No. 892,535.

Specification of Letters Patent.

Patented July 7, 1908.

Application filed September 8, 1905. Serial No. 277,508.

To all whom it may concern:

Be it known that I, CHARLES J. MILLER, of Minneapolis, Hennepin county, Minnesota, have invented certain new and useful Improvements in Store-Service Apparatus, of which the following is a specification.

My invention relates to store service apparatus and particularly to carriers therefor, and the object of my invention is to provide means for taking up the shock or impetus of the carrier as it approaches a station without placing any strain on the line wire or the carrier wheels or axles.

The invention consists generally in friction arms arranged in pairs upon each side of the line wire, one arm of a pair being above the other arm of the same pair.

Further, the invention consists in providing a yielding bearing for the arms to take up the shock or impetus of the carriage.

Further the invention consists in providing means for regulating the resistance of the arms to the entrance of the carriage into the station.

Further, the invention consists in various constructions and combinations, all as hereinafter described and particularly pointed out in the claims.

In the accompanying drawings forming part of this specification, Figure 1 is a side elevation of a station and carrier. Fig. 2 is a plan view of the same. Fig. 3 is a detail view illustrating the position of the friction arms with respect to the line wire. Fig. 4 is a sectional view illustrating in detail the yielding device provided in connection with the friction arms.

In the drawing, 2 represents a hanger, 3 the line wire or way, and 4 a carriage having wheels 5 to rest and travel upon the wire 3. A guide rod 6 is provided in the rear of the hanger 2, beneath which is a plunger 7 having a sliding connection 8 with the said rod, and propelled by means of a cord 9 running over a pulley 10. The forward end 11 of the plunger is adapted to engage the carriage and propel it from the station. An elastic cord 12 is attached to the rear end of the plunger for the purpose of returning it to its normal position. A head 13 is provided on the lower end of the hanger 2 and has a socket 14 to receive a plug 15 secured therein by a set screw 16. One of these sockets is provided upon each side of the line wire, as shown in Fig. 2. The outer end of the plug 15 is flattened, and arms 17 and 18 are se-

cured thereto by means of screws 19, which also pass through yielding washers or blocks 20. The arms 17 are loosely mounted on the screws 19 and slide vertically thereon when the blocks 20 are compressed.

The arms 17 are on substantially the same level as the line wire, and have upwardly turned ends, while the arms 18 have downwardly turned ends, and pins 21 provided on each side of the carriage 4, having antifriction rollers 21', are adapted to pass between the arms 17 and 18, and engaging the contiguous surfaces of said arms check the momentum or impetus of the carriage. At the same time the blocks 20 will yield sufficiently to allow the arms to separate, and offer a yielding resistance to the entrance of the carriage into the station. During the time the pins 21 are passing between the friction arms 75 the wheels 5 will remain upon the line wire without exerting any strain thereon or being raised from their normal position in contact with the wire. The use of these friction arms in pairs upon each side of the line wire 80 will also relieve the carrier axles and wheels of all strain incident to the sudden stopping of the carriage. The screw connection between the arms of the same pair and the yielding washer or block thereon permits the 85 adjustment of the upper arm of each pair toward or from the lower arm, for the purpose of increasing or decreasing the pressure and regulating the degree of separation of the arms according to the weight of the carrier 90 and its speed in approaching the station.

As shown in Fig. 1, the arms will be separated by the pins 21 and their antifriction rollers when the carrier enters a station, and there will be sufficient resistance to the entrance of the pins into the station to gradually check the impetus or momentum of the carrier and bring it to a stop without any jar or shock or rebound or strain upon the wire and the carrier axles and wheels. The friction 100 between the arms and the rollers will be sufficient to offer resistance to the thrust of the plunger until such time as the plunger cord has been tensioned and power accumulated to drive the carrier to the next station. As 105 soon as the plunger has overcome the friction between the arms and rollers, the carrier will be driven from the station, and the plunger being released will return to its normal position.

I claim as my invention:

1. The combination, with a station and a

line wire, of a carriage adapted to travel upon said wire, friction arms arranged in pairs on each side of said wire, and pins mounted on said carriage and adapted to pass between said arms and check the impetus or momentum of said carriage without causing any strain on the line wire, substantially as described.

2. The combination, in a store service apparatus, with a station and a way, of a carrier, friction stop devices having receiving ends above and below the level of said way and arranged to prevent vertical movement of the carrier as it enters the station and to check its impetus or momentum without causing any strain on said way.

3. The combination, in a store service apparatus, with a station and a line wire, of a carrier adapted to rest and travel upon said wire, friction arms arranged in the path of said carrier and having bearings which yield and permit vertical movement of said arms and preventing vertical movement of said carrier, for the purpose specified.

4. The combination, in a store service apparatus with a station and a line wire, of a carrier adapted to rest and travel upon said wire, friction arms arranged one above another in pairs upon each side of the line wire, the upper arms being upon substantially the same level as the wire and having upwardly turned outer ends and the lower ends being below the level of said wire and having downwardly turned outer ends and said arms being sufficiently near together to engage said carrier and retard or check its momentum without causing strain on the wire.

5. The combination, with a station and a line wire, of a carrier adapted to rest and travel upon said wire, friction arms arranged one above another in pairs upon each side of said wire, the upper arms being loosely mounted, yielding washers or blocks forming bearings for said upper arms, and said arms being adapted to engage said carrier and check the impetus or momentum of the same as it enters the station, substantially as described.

6. The combination, in a store service apparatus, with a station and a way, of a carrier adapted to travel on said way, arms arranged in pairs upon each side of said carrier, one arm of a pair being above the other arm

of the same pair, means for adjusting the mountings of said arms to vary the resistance to separation between those of the same pair, and means provided on said carrier and adapted to engage said arms, substantially as described.

7. The combination, in a store service apparatus, with a station and a way, of friction arms arranged in pairs upon each side of said way, one arm of each pair being arranged above the other arm of the same pair, means adjustably connecting the arms of the same pair, and the upper arms having a yielding vertical movement, a carrier adapted to travel on said way and having means to pass between said arms and engage the same, substantially as described.

8. In a store service apparatus, a station and a way and a carrier therefor, in combination with friction arms arranged to engage said carrier upon its entrance into the station, the upper friction arms arresting or checking the momentum of the carrier and the lower friction arms raising the carrier slightly and relieving the way of strain thereon.

9. In a store service apparatus, a station, a way and a carrier therefor, in combination with friction arms arranged upon different levels, some of said arms having yielding bearings and engaging said carrier and resisting its entrance into the station.

10. In a store service apparatus a station, a way and a carrier therefor in combination with upper and lower friction arms, said upper arms furnishing a yielding resistance to the entrance of the carrier into the station and said lower arms raising the carrier slightly and relieving the way of strain thereon.

11. In a store service apparatus, a station, a way and a carrier therefor, in combination with friction devices arranged one above another on each side of said way and said carrier having means to pass between said devices and engage the same, and whereby the impetus or momentum of the carrier will be checked, substantially as described.

In witness whereof, I have hereunto set my hand this 31st day of August 1905.

CHARLES J. MILLER.
